UNITED STATES PATENT OFFICE.

JOHN SHERMAN McCHESNEY, OF CHICAGO, ILLINOIS, ASSIGNOR, BY MESNE ASSIGNMENTS, TO CARY MANUFACTURING CO., OF BROOKLYN, NEW YORK, A CORPORATION OF NEW YORK.

WIRE-BANDING MACHINE.

Application filed August 8, 1918. Serial No. 248,832.

My invention relates to machines for wire-banding packages, its general objects being to provide a power driven machine designed for quickly and effectively encircling a box or other package with a wire band tightened to a predetermined tension, and fastened under this tension, all with a minimum requirement of time and of attention on the part of the operator. Viewed in some of its more particular aspects, my invention aims to provide power-driven means for feeding the end of a supply of wire into a loop adapted to encircle the object which is to be banded, also power driven means for tightening the loop about the package to a predetermined tension, for gripping relatively spaced portions of the loop, for severing the loop from the supply of wire and for effectively joining adjacent portions of the loop while the latter is thus tensioned about the package. For these purposes, my invention aims to provide means for automatically feeding a predetermined length of wire into a loop formation, for gripping the free end portion of the wire, for then tightening the loop about the package and gripping another portion of the loop, and for thereafter severing the entire loop from the supply of wire and permanently joining adjacent end portions of the loop. Furthermore, my invention aims to provide means for joining loop ends while overlapped parallel to each other and substantially parallel to a side of the package, to provide for effecting this joining with a minimum of space between the overlapped loop ends and the package, and for automatically introducing and retracting the means which space the overlapped loop ends from the package during the joining of the loop ends. My invention also aims to provide simple means for electrically welding the ends of the wire loop to each other, and preferably for weld-joining them to each other at a number of spaced lines or points; by applying current for a portion of the time during which the wire loop parts are pressed together at these points; also, for making the actuating of the wire-severing and the welding apparatus automatically responsive to a predetermined tensioning of the loop, thereby eliminating both the necessity of vigilance on the part of the operator of the machine and any loss of time between the reaching of the desired tensioning

and the actuating of the wire-severing and welding portions of the machine. My invention also aims to provide for such purposes a machine of relatively simple construction, which will be positive in its action, which will automatically return various operative elements of the machine to their starting positions, and which will avoid a damaging of the machine in the event that the banding wire should break during the tensioning. Furthermore, my invention aims to provide a machine which will be equally adaptable for use with round or flat wire and with wires varying in diameter or thickness, and one in which the extent of various operations is controlled by clutches of relatively simple and durable construction. Still other objects of my invention will appear from the following specification and from the accompanying drawings, in which

Fig. 1 is a front elevation of a machine embodying my invention, showing the same in its wire-feeding position.

Fig. 2 is a plan view of the same.

Fig. 3 is an enlarged and fragmentary longitudinal section taken substantially centrally of the machine of Figs. 1 and 2 and showing the mechanism in position for making one of the welds after the wire of the loop has been severed from the supply of wire.

Fig. 4 is a similar fragmentary section showing the mechanism in the position in which it feeds the wire into the raceway.

Figs. 5 and 6 are vertical sections taken through Fig. 4 along the lines 5-5 and 6-6 respectively.

Fig. 7 is a detail of the mechanism showing the operation of the wire cutter.

Fig. 8 is a similar detail showing the cams controlling the three welding electrodes.

Fig. 9 is a fragmentary detail showing the resilient connection between the lever operating one of the wire-gripping clamps and the mechanism for starting the wire feeding rollers and for rendering the wire-tensioning rollers inoperative.

Fig. 10 is an enlarged fragmentary vertical section taken through Fig. 4 along the line 10-10 and showing the face of the clutch controlling the wire-clamping and welding mechanism.

Fig. 11 is a transverse section through Fig. 10 along the line 11-11.

Fig. 12 is a transverse section through Fig. 11 along the zigzag line 12—12.

Figs. 13 and 14 are perspective views of the barrel and clutch pin respectively of the 5 clutch of Figs. 10, 11 and 12.

Fig. 15 is a plan view of joined wire loop portions indicating the spacing of the welds.

Fig. 16 is a longitudinal section through the same.

10 Fig. 17 is a perspective detail of part of the mechanism for tripping the clutch controlling the wire-tensioning means.

15 Fig. 18 is a further detail view of the mechanism for tripping the clutch controlling the wire-tensioning means.

Fig. 19 is a detail view of the commutating arrangement for controlling the supply of current to the electrodes.

In the embodiment of the drawings, the 20 machine of my invention includes a frame 1 supporting a table 2 surmounted by a channel-sectioned raceway 3 somewhat larger than the maximum size of box or package 4 which is to be banded. The raceway 3 25 has a bottom portion cut away and the table 2 has a longitudinal slot 5 in vertical alignment with the raceway and also substantially in alignment with an entrance runway 6 extending from the juncture of a pair 30 of feeding rolls 8 toward the said slot, and with a guideway 7 interposed between the feeding rolls 8 and a pair of wire-tensioning rolls 69, each of the said pairs of rolls being supported by the frame 1. The wire-feeding 35 rolls are connected by gearing with a gear 9 loosely mounted on a shaft 10, which shaft 10 is connected by bevel gears to a continuously rotating drive shaft 11. The shaft 10 also carries a clutch adapted when 40 actuated to connect this shaft for a single revolution with the gear 9, and the transmission between this gear and the wire-feeding rolls is so proportioned that a single revolution of the shaft 10 will feed a pre- 45 determined length of wire into the raceway, namely such a length as will bring the free end 15 of the wire to the point shown in Fig. 3; that is to say, to a point slightly beyond the welding electrodes 16, 17 and 18.

50 The table 2 is also equipped with transverse slots suitably arranged for serving as guideways for slides 19, 20 and 21, all three of which slides are equipped on their lower faces with racks 22 (shown more clearly in 55 Figure 6), said racks 22 meshing with pinions 23 on a shaft 24 having at one end a handle 25 whereby this shaft may be rotated for moving the slides 19, 20 and 21 either to their operative positions as shown in 60 Figs. 2 and 3, or to inoperative positions in which the said slides are retracted clear of the slot 5.

Associated with the slide 19 is a plunger 26 connected through a spring 27 with a 65 slide 28 carrying a roller 29 which engages

a cam 30 on a welder shaft 31 extending longitudinally of the machine at some distance below the raceway. The welder shaft 31 also carries three cams spaced from each other as shown in Fig. 8 and arranged respectively for imparting forcible upward movement to the electrodes 16, 17 and 18, which three electrodes are all slidably mounted in a guide 32 carried by and insulated from the frame 1 of the machine. 70 These electrodes are disposed opposite different portions of the slide 20, while the slide 21 has opposed to it a clamping jaw 33 arranged for upward movement by a pair of toggle levers 34 and 35 (Fig. 1), the former of which levers is bent at an angle and extended to afford a lever terminating in a handle 36. The welder shaft 31 also carries a cam 37 operatively connected to a knife or cutter 38, which knife is slidably mounted and preferably disposed close to the forward end of the runway 6, and which knife is withdrawn by a spring 39, see Figure 4, to a position entirely below the slot in the said runway when the wire is fed into the 80 machine. From the above description, it will be seen that after wire has been fed into a loop with the aid of the runway, so that the free end 15 of the wire overlaps a portion of the supply part of the wire under 85 the slide 20, the resulting loop may be clamped respectively at opposite sides of the slide 20 between the slide 19 and the plunger 26, and between the slide 21 and the clamping jaw 33. Then if current from a 90 suitable source is connected respectively to the frame of the machine and to the guide 32, the successive upward movement of the electrodes 16, 17 and 18 will successively 95 weld the overlapped portions of the loop to each other at three relatively spaced points. Likewise, it will be obvious that a forcible upward movement of the cutter 38 by the cam 37 will sever the loop from the supply 100 of wire, for which purpose the cam 37 is 105 preferably positioned rotationally in advance of the cams associated with the welding electrodes, so that the severing of the wire is effected prior to the welding operations. 110

When the wire is fed into the raceway 3 by means of the mechanically rotated rollers 8, its normal resistance to bending will cause it to conform substantially to the contour of the interior of this channel. Then the slides 19, 20 and 21 are moved into their operative positions of Figs. 2 and 3 (or between the box 4 on the one hand and the electrodes as well as the plunger 26 and the 120 clamping jaw 33) after which the wire of the loop is clamped between the slide 21 and the jaw 33 by moving the hand lever 36 of Fig. 1 in the direction of the arrow. This clamping holds the free end of the wire, so 125 that the loop can then be tensioned around 130

the package by means of the power-driven rollers 69, both of which rollers are operatively connected through a gear 39 and a worm 40 to driving mechanism controlled by a clutch 41. The tensioning rollers 69 are mounted on shafts carried by a slide 42 which is horizontally movable on the frame 1 of the machine towards the raceway, but which is resisted as to such movement by a spring 43, the tension of which spring may be adjusted by suitable means, such as a threaded bushing 44. This spring 43 holds the slide 42 in its normal position while the rollers 69 are retracting the wire and therefore tensioning the loop, until the strain of this tensioning exceeds the pressure for which the spring 43 is adjusted. Then a continued rotation of the rollers 69 compresses the spring 43, thereby moving the slide 42 forwardly of the machine and effectively discontinuing the tensioning action of the wire, so that the extent of this tensioning is predetermined by the adjustment of the spring 43.

The slide 42 also carries a rod 45 having at its forward end a hinged tip 46 normally held in alignment with the rod 45 by a spring 51, the position of which is indicated in Figures 3 and 4 and which spring is arranged in any desired manner obvious to those skilled in the art, to the end that said hinged tip 46 will project normally into the path of a pivoted latch 47, which latch is normally drawn by a spring 52 into a position in which it holds a clutch 48 inoperative. When the movement of the slide 42 forces the rod 45 forward, the tip 46 moves this latch 47 out of its latching position, thus releasing the clutch and connecting the welder shaft 31 for one revolution with a gear 53, which gear is loose with respect to the shaft 31 and is continuously revolved by means of a gear 54 on the drive shaft 11. This clutch connects the welder shaft 31 with a continuously rotating drive shaft 11, so that the forward movement of the slide 42 and of the rod 45 carried by the latter effects the connection of the welder shaft 31 to the source of power and therefore starts the successive operations of the elements actuated by the cams mounted on this welder shaft. As soon as the clutch 48 has thus been actuated, the hinge end 46 of the rod 45 is forced out of the way by a stripper arm 50 carried by a part of the clutch, thus permitting the spring 52 to return the latch 47, so that this latch will stop the rotation at the end of a single revolution.

When the shaft 31 is thus rotated, the cam 30 carried by the same first raises the jaw 26 so as to clamp a part of the wire loop between the latter and the slide 20, and the cam 37 then raises the cutter 38, thereby severing the supply end of the wire from the loop portions. This leaves the freshly

severed end of the loop free to be forced against the slide 20 both by the upward thrust of the cutter (as shown in Fig. 3) and by the successive upward movements of the electrodes 16, 17 and 18, so that the overlapped parts of the loop can be welded to each other at three relatively spaced points. Before the shaft 31 completes its revolution, the jaw 26 will be retracted by gravity thus releasing the grip on the wire loop and leaving the latter gripped only between the jaw 33 and the slide 21. Then a manual raising of the lever 36 releases this last grip on the wire loop, after which a partial rotation of the pinions controlled by the handle 25 withdraws the slides 19, 20 and 21 from their position between the package and the wire loop, thus permitting the banded package to be removed from the table.

In practice, three movable slides can be made sufficiently thin so that their removal will not cause an excessive loosening of the band of the package, and particularly not if the tensioning of the loop was substantially symmetrical with respect to the forward and rear ends of the package. With this in mind, I desirably equip the table with yielding stops for resisting the tensioning of the wire loop, after the general manner shown in United States Patent No. 1,324,590, patented December 9, 1919, by A. G. Guenther, for wire tying machine. Thus, in the drawings I have shown the stop formation as comprising a pair of pivoted jaws 56 continually forced in one direction by springs 57 and hence offering a yielding resistance to the package, so that the package will be moved somewhat towards the rear of the machine during the tensioning and will therefore distribute the tensioning effect over the forward and rear ends of the package.

When the clamping jaw 33 is lowered by the raising of the lever 36 so as to release the free end of the supply of wire, the continued action of the retracting rolls 69 will tend to withdraw the supply wire entirely from the machine and would pull the tip of this wire beyond the feeding rolls 8 if left unchecked. However, the releasing of the end of the supply wire also permits the spring 43 to return the slide 42 which carries the wire-returning rollers. When thus returned, the wire-returning rollers are automatically thrown out of effective action before they have returned the supply wire to any considerable extent. For this purpose, Figure 3 shows the upper of these rolls as mounted on a bearing carried by the upper of a pair of toggle-joint levers, which lever has a shoulder 58 so arranged that a forward thrust on this shoulder will tend to unbend the toggle against the pressure of a spring 59 and will thereby sepa-

rate the rollers 69 so that they will no longer grip the wire between them. To effect this separation, I provide a stop 60 so disposed as to be in the path of the shoulder 58 when the slide 42 is being returned to its starting position by the spring 43, thus automatically putting the retracting rolls out of action. This stop 60 is desirably formed as a part of a lever 61 continually pressed in one direction by a spring 62 but adapted to be moved against the pressure of this spring by a link 63. This link 63 is connected to the toggle lever 35 as shown in Figure 1, so that the link will be drawn forward when the lever 36 is depressed for gripping the wire loop and starting the wire feeding rolls.

The toggle mechanism controlled by the lever 36 is also connected by a link 64 with toggle levers 65 controlling the wire-feeding rollers 8 as also shown in Fig. 1, consequently, when the wire has been fed into loop formation, the single downward movement of the lever 36 releases the wire-feeding rolls from their grip on the wire and permits the spring 59 to force the wire-retracting rolls into operative engagement with the wire.

For the single-revolution clutch as needed both on a shaft 10 and on a counter shaft 31, I may employ a type such as that pictured in Figs. 10 and 14 inclusive, namely one in which a barrel 48 is keyed to the shaft and has an approximately cylindrical portion forming a bearing for a gear loosely rotatable on the same. The hub of the gear is provided with a number of substantially hemispherical openings extending parallel to the axis of the shaft and adapted to align with a corresponding recess in the hub of the barrel, so that the two recess portions will together form a tubular bore. Mounted in this bore is a clutch pin 65^a having a portion cut away so as to align with the adjacent part of the hub of the barrel when this pin is in one position, as shown in Fig. 11. However, the pin carries an arm 66 engaged by a spring 67 which normally tends to move this arm into the position of Fig. 12, thereby tilting the cut-away part of the clutch pin so that this part connects the hub of the clutch barrel with the gear and thereby causes the two to rotate together. In operation the arm 66 engages the latch 47, thereby compressing the spring 67 and holding the arm 66 in the position of Fig. 10, in which position the clutch pin permits the gear to rotate freely upon the hub of the barrel which is keyed to the shaft. When the latch 47 is forced out of the way by the movement of the rod 45 as previously described, the spring 67 moves the arm 66 to the position of Fig. 12 as soon as one of the openings in the gear is opposite the opening which houses the cut-away portion of the clutch pin, thus permitting the spring 67 to move the arm 66 and

the clutch pin to the position of Fig. 12. The gear is then operatively connected with the shaft and rotates with the latter until the arm 66 strikes the latch 47 when the clutch has completed one revolution, whereupon this latch returns the arm 66 to its position of Fig. 10 and thereby causes the clutch pin to disengage the gear from the shaft.

Reviewing the operation of the machine, this is started with driving shaft 11 rotating continuously and with the transverse slides 19, 20 and 21 retracted so as to leave the longitudinal slot 5 in the table fully open, this being the position after the previously banded package has been withdrawn. In turning the handle 25 so as to rotate the pinions 23, the three slides are moved across the slot 5 into the positions shown in Fig. 2, and in so doing the tip of the slide 21 engages one end of a bell-crank lever 14, thereby causing the other end of this lever (as shown in Fig. 5) to move a slide 68. This slide releases the latch 69^a, which normally prevents the operation of a clutch connecting the continuously driven shaft 10 with the gear 9 which is connected by other gears with the wire feeding rolls 8 for a single revolution of the shaft 10. The feeding rolls therefore force the supply of wire into the raceway 3, so that when the clutch disengages the gear 9 from the shaft 10 (after the manner heretofore described in connection with Figs. 10 to 14 inclusive) the wire will be disposed in a loop formation urged outward by its own resiliency into the raceway 3 and with the extreme tip 15 of the wire disposed substantially as shown in Fig. 3, or between the slides 19 and 20. I then depress the handle 36, thereby gripping the free end portion of the wire between the slide 20 and the rear portion of the raceway, so as to obtain a hold against which the wire may be tensioned about the package, which package may be inserted at any time prior to the movement of the lever 36. The same downward movement of this lever 36 also drives both the links 64 and 63 forward, and each of these links operates the toggle joint connected thereto. Consequently, the link 64 raises the upper wire-feeding roller so as to permit the wire to slide freely between the feeding rolls, while the link 63 overcomes the pressure of the spring 62 and thereby moves the stop 60 out of the path of the shoulder 58, so that the spring 59 can force the wire-retracting rolls 69 into effective engagement with the wire. A downward movement of the arm 36 of the angular lever comprising the arms 34 and 36 also acts through its toggle connection with the link 35 and through a plunger 81 to rock a bell-crank lever 92 as shown in Figure 1. This movement of the plunger 81 is resisted

by a spring 83 in the casing 82 in which this plunger is slidably mounted (as shown in Figure 9), so as to compensate for the effective difference in the joint lengths of the 5 toggle arms 34 and 35 in their extreme positions, the rocking lever 92 is connected by a lever 73 to a rod 68 (see Figure 1) which rod normally holds a clutch latch 94 in operative position against the pressure of a 10 spring 83, as shown in Figures 17 and 18. This latch 94 normally acts as a detent for the trip arm 75 of the clutch (shown in Figure 18) which connects the continuously rotating shaft 11 with gears interposed between this shaft and the worm 40 used for actuating the wire tensioning rollers. When the handle lever 36 is depressed and the rod 68 is moved towards the right of Figure 1 through the above described connections, it 15 rocks the detent arm 94 towards the right or out of engagement with the trip arm 75, thereby permitting the clutch to operate. But as soon as this has occurred, a suitably connected hook-arm 71 draws the rod 68 off 20 the face of the detent 94 and hence permits the spring 85 to return the detent to its normal position, so that the clutch is stopped at the end of a single revolution.

When thus actuated, the rolls 69 retract 25 the supply of wire, thereby tensioning the loop about the package and moving the latter somewhat against the pressure of the spring 57 (Fig. 2) to distribute the tensioning with respect to the package. The same 30 movement of the worm wheel 39 which rotates the tensioning rollers also tends to impart a longitudinal movement to the slide 42 which carries these rollers. As soon as this latter strain exceeds that for which the 35 spring 43 is adjusted, so that when the loop has been tensioned to the predetermined extent, the slide 42 moves forward and thrusts the hinged end 46 of the rod 45 against the clutch latch 47. This actuates the clutch 40 controlling the welder shaft 31 and causes the latter to rotate for a single revolution, thereby actuating the various cam mechanisms for gripping added loop portions, for turning on the current, and for severing the 45 loop from the supply of wire. To make the welding more effective, I desirably provide a commutator 73 on the shaft 31, so arranged as to connect with a spring-pressed brush 74 only for a part of the time during which 50 each electrode is pressed against the wire, these parts being shown in detail in Fig. 19 but partly omitted to simplify Fig. 1. I also desirably provide springs 72 for aiding gravity in retracting the electrodes, 16, 17 55 and 18.

It is to be noted that band-cutter 38 is operated automatically by the cam 37 for severing the band at a point adjacent to the union effected between terminal portions of 60 a loop into which the band is adapted to be

formed around the package, see Figures 1, 3 and 4. The band-cutter is in shearing relation to an end portion of the guide 6 which part acts to perform the function of means for retaining an end portion of a band when the latter is looped around a package. Said cutter 38 and the gripper 26 are operated automatically to position one end portion of a band into physical contact with another end portion of said band when looped, and to 70 retain said end portions of the band in such physical contact during the operation thereon of band-securing means by which the two end portions of the band are joined or united. In the example of the invention 75 herein disclosed, the band-securing means is constituted by the welding mechanism electrically operated to join the end portions of the loop by a plurality of spot welds, as shown in Figures 15 and 16.

However, while I have illustrated and described both the clutch arrangement and other parts of my mechanism in certain suitable embodiments, I do not wish to be limited to these or other details of the construction and arrangement here described as the same might obviously be varied in many ways without departing from the spirit of my invention. Likewise, while I have used the term "point" in connection with welding, I do not mean to be limited to diminutive sizes of spot welds, since the welding might equally well be in the form of lines or strips extending from edge to edge of the wire band, as shown in dotted lines in Fig. 15. So also, I do not wish to be limited to any particular cross-section of wire, but have used this term in the broad significance in which it may designate a wide variety of sections.

I claim as my invention:—

1. In a package banding mechanism, means for feeding a band into position for encircling a package and with the intended terminals of said band in substantially parallel relation to each other, means for retaining one terminal portion of said band in fixed relation to the other terminal portion of said band, means for retracting said band while so held to thereby place tension on said band, said band-retracting means being separate from band-feeding means, and means for joining the substantially parallel portions of said band while said band is under tension.

2. In a package banding mechanism, means for feeding a band into loop formation and with the intended terminal portions of said loop in substantially parallel relation with respect to each other, means for retaining one terminal portion of the looped band in a fixed relation to the other terminal portion of said looped band, means for retracting said band and thereby placing the loop under tension around a package, means

for severing the loop from the band supply, and means for joining the substantially parallel terminal portions of said looped band.

3. In an appliance for banding an object with wire, power-driven rollers arranged for retracting the wire to tension the same about the object, a slidably mounted support for the rollers, and yielding means resisting the sliding of the support.

4. In an appliance for banding an object with wire, means for feeding the wire into a loop, means for gripping a portion of said loop, and means for simultaneously actuating the gripping means and for releasing 15 the wire feeding means from operative engagement with the wire.

5. In an appliance for banding an object with wire, a raceway substantially encircling the object, means for feeding a predetermined length of wire into the raceway to form a loop encircling the object and having its free end substantially at a predetermined position, means for gripping a portion of the loop, and means responsive to the actuating of the said gripping means for releasing 25 the wire-feeding means from engagement with the wire.

6. In an appliance for banding an object with wire, means for feeding the wire into a loop, means for gripping the wire at one of the intended terminals of the loop, means for releasing the feed means from operative engagement with the wire when a predetermined length of wire is fed to produce the 35 loop, means for retracting the wire to thereby tension the loop around an object, and means for setting the wire retracting means into action when the wire feed means are moved out of operative engagement with the 40 wire.

7. In an appliance for banding an object with wire, a table supporting the package entirely above its top and having a slot facing the package and permitting wire to be 45 looped about the package with a portion of the wire disposed below the top of the table, and a spacer member movable transversely across the said slot between the package and the wire loop.

8. In an appliance for banding an object with wire, a package-supporting table provided with a slot within which is adapted to be positioned a portion of a loop which encircles a package, a member movable relatively to said table and transversely with respect to the slot therein, means for feeding a wire to produce said loop, and means controllable by the movement of said element for setting into operation said wire-feeding 55 means.

9. In a wire-banding appliance, a package-supporting table provided with a slot, a plurality of elements movable relatively to said slot, means for imparting movement 65 concurrently to said elements, means for

feeding wire into a loop formation adapted to encircle an object, and means controllable by the movement of one of said elements for setting into action said wire-feeding means.

10. In an appliance for wire-banding an object, a support for the object having a slot so located as to permit a portion of the wire band to be disposed below said support, movable means extending transversely of the slot for spacing the said wire portions 75 from the object, and means for clamping parts of the said wire portion against the said movable means.

11. In an appliance for wire-banding an object, a support for the object, having a slot 80 so located as to permit portions of the wire band to be disposed below said support, and having another slot extending transversely of the aforesaid slot, a slide movable in the transverse slot across the first named slot, 85 and means for clamping a portion of the wire band against the slide.

12. In an appliance for banding an object, an object supporting member, and a plurality of devices for clamping relatively 90 spaced portions of a banding wire, each of said devices including a pair of co-operable members one of which is movable parallel to the bottom of an object and the other of which is movable toward or from said object, transversely thereto.

13. In an appliance for wire-banding an object, a support for the object, and plural means for clamping relatively spaced portions of the banding wire; each of the said means including a pair of members, one of which is movable into and out of a position between the wire band and the object, and the other of which is movable towards and away from the portion of the banding wire 105 spaced from the object by the aforesaid member.

14. In an appliance for wire-banding an object, a table on which the bottom of the object is adapted to rest, the said table having 110 a slot for permitting the banding wire to extend below portions of the table, a clamping element adapted to be interposed between the bottom of an object and a portion of the banding wire, and a second clamping 115 element movable transversely of the bottom of the object and adapted to clamp the banding wire between itself and the first named clamping element.

15. In an appliance for wire-banding a package, means for feeding a wire in loop formation around the package with portions of the wire loop relatively overlapping, means for gripping one portion of the wire loop, means for tensioning the wire loop, and 125 means controllable by said gripping means for setting into action said wire tensioning means.

16. In an appliance for wire-banding a package, means for feeding a wire in loop 130

- formation around the package with portions of the wire loop relatively overlapping, means for gripping one portion of the wire loop, wire-tensioning means and means controlled by the movement of said gripping means for shifting the wire tensioning means into a service relation to the wire. 5
17. In an appliance for wire banding an object, wire feeding means for producing a loop with terminal portions of said loop relatively overlapping, means for gripping one terminal portion of said loop, means for tensioning said loop subsequently to the gripping thereof, and means for gripping another portion of said loop subsequently to the tensioning thereof. 10
18. In a wire-banding appliance, a table having a top disposed for supporting the object which is to be banded and having the said top provided with a slot, a plurality of elements arranged for movement across the said slot, means for moving the said elements across the slot, means for feeding wire into a loop encircling both the object and the said elements; means for tensioning the said loop and for securing portions thereof to each other, and means for thereafter retracting the said elements. 20
19. In an appliance for wire-banding an object, stationary means including a support for the object and a raceway partly encircling the object, the raceway having a gap therein, cooperable welding electrodes adjacent to said gap, means for feeding wire into the raceway to form a loop encircling the object and having its terminals disposed between the said electrodes, means for tensioning the loop and means for thereafter actuating the welding electrodes to join the loop terminals to each other. 30
20. In an appliance for banding packages with wire, wire-feeding means operable for the formation of a loop adapted to encircle a package, wire-tensioning means operable for retracting the wire of the loop so as to tighten said loop around the package, wire-holding means actuated to fixedly retain one terminal portion of said loop in an overlapping relation to the other terminal portion of said loop, and controlling means whereby the wire-feeding means is shifted out of operative relation to the wire and the wire tensioning means is brought into service subsequently to the operation of fixedly retaining one terminal of said wire by said wire holding means. 50
21. In an appliance for banding packages with wire, wire-feeding means operable for the formation of a loop adapted to encircle a package, wire-tensioning means operable for retracting the wire of the loop so as to tighten said loop around the package, wire-holding means actuated to fixedly retain one terminal portion of said loop in an overlapping relation to the other terminal portion 65
- of said loop, means for joining or uniting the lapped terminal portions of said loop, and controlling means effective in shifting the wire-feeding means to an out of service relation to the wire and for actuating the wire-tension means and the wire joining means in successive order. 70
22. In an appliance for wire-banding an object, a support for the object, means for disposing wire in loop formation about the object, three spacers removably disposed between the object and the loop, means cooperating respectively with two of the spacers for gripping relatively spaced portions of the wire loop, and means cooperating with the third spacer for welding loop portions of the wire to each other. 75
23. In an appliance for uniting adjacent portions of a wire band disposed about a package, means for effecting the said uniting, spacer members spacing the package from the wire portions which are being united, a stationary support arranged for supporting both the package and the aforesaid elements and means movably mounted on the support for simultaneously withdrawing the spacer members from their said spacing position. 80
24. In an appliance for banding objects with wire, wire-feeding means operable for the formation of a loop adapted to encircle the object, means for fixedly retaining one terminal portion of said loop in an overlapping relation to the other terminal portion of the loop, tensioning means for tightening the loop around the object, and controlling means actuated concurrently with said retaining means for shifting the wire-feeding means out of service relation to the wire and for shifting the tensioning means into a service relation to the wire. 90
25. In an appliance for electrically uniting overlapping end portions of a wire band encircling an object, means for tensioning the band about the object, and consecutively operating means for gripping overlapped wire band portions while the band is under tension, for severing the wire loop from the supply of wire and for electrically welding overlapped wire portions to each other. 100
26. In an appliance for electrically uniting overlapping end portions of a wire loop, consecutively operating means for gripping such overlapping wire portions, for severing the wire loop from the supply of wire, and for electrically welding the overlapped wire portions to each other at a plurality of relatively spaced points. 110
27. In an appliance for banding a package with wire initially disposed in a loop formation loosely encircling the package and having the tip of the wire overlapping another wire portion, means for gripping a loop portion of the free end of the wire at a distance from the tip of the latter, means 125
- 130

for tensioning the wire loop about the package, means controllable by said gripping means for shifting the wire tensioning means into a service relation to the wire subsequently to a cessation in the operation of the wire-feeding means to produce the loop, means for severing the wire from the supply adjacent to the said gripping means and for pressing the severed end of the wire into closely overlapping relation to a loop portion of the wire, and means for thereafter securing the said closely overlapped wire portions to each other.

28. In an appliance for wire-banding a package, means for feeding the end of a supply of wire into a loop encircling the package and having the extreme tip of the wire adjacent to another portion of the wire, and having the loop portion immediately back of the said tip diverging angularly from the supply portion of the wire adjacent thereto; a clamping element disposed between the said angularly diverging portions, means disposed within the wire-loop for clamping a portion of the loop against the first named clamping element; means for tensioning the wire about the package when the said loop portion is thus clamped, cutting means for severing the supply of wire adjacent to the said clamping element, and means for thereafter securing the wire loop portion thus severed from the supply of wire to an adjacent loop portion.

29. The method of banding a package with wire, which consists in forming a loop encircling a package and positioning the free end portion of said wire loop in an overlapping relation to another portion of said loop, holding the free end portion of said loop in fixed relation to the overlapped portion, tensioning the loop around the package by a pull angularly diverging from the fixedly held end portion of the wire, again holding the wire of the loop by gripping the same at a point beyond the end first held, severing the wire at a point adjacent the first holding point, and welding by heat and pressure the two end portions in the area intermediate the two specified holding points.

30. In an appliance for banding objects with wire, wire-feeding means operable for the formation of a loop with a terminal portion of the wire in lapping relation to a portion of the loop, a plurality of wire holding devices one of which engages the wire at its terminal portion and the other of which engages the wire leading to the supply, means for successively actuating said wire-holding devices to grip the wire at different stages in the operation of banding the object, means for tensioning the loop subsequently to the engagement with the wire of that holding device which retains the terminal portion fixedly in position, means for joining the overlapped portions of the wire in

the area intermediate the engagement therewith of the said plurality of wire-holding means, and means for severing the wire.

31. In an appliance for banding objects with wire, a package support, a member movable relatively to the package support in a plane substantially parallel to the surface of a package, means for looping a wire around the package and crosswise of said member, with said member intermediate the surface of the package and the wire, a second member co-operable with the first member and movable relatively thereto for engagement with the wire, and means for shifting the first member out of operative relation to the second member and for withdrawing said first member from its place between the wire and the package.

32. In an appliance for banding objects with wire, means operable for feeding wire to produce a loop and for retracting the wire of said loop into tight engagement with a package, a plurality of holding devices engageable with overlapping portions of said wire adjacent the terminals of the loop, a welding member movable into position between the wire and the surface of a package, means for shifting the welding member into and out of a service relation to the lapping portions of a wire, a second welding member movable relatively to the first welding member, and means for actuating said second welding member with respect to the first welding member for the application of pressure and for feeding electrical current to the lapping wire portions by the co-operation of said two named welding electrodes.

33. In an appliance for wire-banding an object, means engaging a wire to feed it about the object, means for thereafter gripping a portion of the wire, wire-retracting means for tensioning the resulting loop about the object; and cooperating means for actuating the gripping means, releasing the wire-feeding means from engagement with the wire, and actuating the wire-retracting means.

34. Mechanism as per claim 33, with the said cooperating means arranged for providing an interval of time between the actuating of the gripping and wire-feeding means and the actuating of the wire-retracting means.

35. In an appliance for banding an object with wire, wire feeding means operable for the formation of a loop with a terminal portion of said wire in lapping relation to a part of the loop, means for gripping a terminal portion of the wire subsequently to the formation of the loop, wire-tensioning means, co-operating means for actuating the gripping means at an interval intermediate the cessation in the operation of feeding the wire and in the operation of tensioning the wire, and resilient means associated with

said co-operating means for producing an appreciable interval of time between the actuation of the gripping and feeding means and the actuation of the tensioning means.

5 36. In an appliance of the class described, wire-pulling means including a pair of opposed rollers engaging the wire, a worm wheel connected to one of the rollers, a longitudinally immovable screw engaging the 70 worm wheel, a slidable carrier for the worm-wheel and the rollers, and yielding means for resisting a sliding of the carrier.

10 37. In an appliance of the class described, wire-pulling means including a pair of opposed rollers engaging the wire, a worm wheel connected to one of the rollers, a longitudinally immovable screw engaging the 75 worm wheel, a slidable carrier for the worm-wheel and the rollers, spring means continuously urging the carrier in the same direction in which the wire is pulled, and means engaged by the carrier at its extreme movement in the said direction for operatively disengaging the rollers from the 80 wire.

25 38. In an appliance for banding an object with wire, wire-tensioning means including a slidable carrier, co-operable wire rollers supported thereby, means for imparting rotative movement to said rollers, means for moving said carrier in the direction in which the wire is pulled for tensioning the same, means engageable by the carrier as it approaches the limit of its movement for shifting the co-operable rolls out of service relation to the wire, and means for controlling the action of said roll-disengaging means.

30 39. In an appliance including separate wire-feeding and wire-retracting means, means for gripping a portion of the wire after it has been fed; concurrently acting means for operating the gripping means, releasing the wire-feeding means from operative engagement with the wire, and moving the wire-retracting means into engagement with the wire; and means associated with the said concurrently acting means but operating subsequently thereto for actuating the wire-retracting means.

45 40. In an appliance for wire-banding an object, means for tensioning a wire terminating in a loop disposed about the object and having the free end of the wire overlapping a portion of the loop, means for gripping the wire loop at two points other than the said overlapped parts, means for securing the overlapped parts to each other, and a means for severing the wire of the loop from the supply of wire while the wire 105 is under tension and after the securing means have been set in operation.

50 41. In an appliance for wire-banding an object, means for tensioning a wire terminating in a loop disposed about the object and having the free end of the wire overlapping 110

a portion of the loop, means for gripping the wire loop at two points other than the said overlapped parts, means for securing the overlapped parts to each other, and means for discontinuing the tensioning of the wire 70 after the securing means have been set in operation.

42. In an appliance for wire-banding an object, means for tensioning a wire terminating in a loop disposed about the object 75 and having the free end of the wire overlapping a portion of the loop, means for gripping the wire loop at two points other than the said overlapped parts, means for welding the overlapped parts to each other 80 by a number of consecutively formed spaced welds, and means for discontinuing the tensioning after at least one of the welds has been effected.

43. In a wire-banding appliance, wire-tensioning means, a spring-resisted slide carrying the latter, welding means for adjoining portions of the wire band, a clutch controlling the welding means, and means carried by the slide for actuating the said 90 clutch.

44. In a wire-banding appliance, wire-tensioning means, a spring-resisted slide carrying the latter, welding means for adjoining portions of the wire band, a clutch 95 controlling the welding means, a latch normally holding the clutch inoperative, and means carried by the slide for releasing the latch from its normal position when the slide is moved against the spring resistance 100 associated therewith.

45. In an appliance for electrically uniting overlapping end portions of a wire loop, cam actuated means for successively gripping a portion of the said loop, for severing the loop from the supply of wire, and for consecutively pressing the overlapped wire portions against each other at a plurality of relatively spaced points; in combination with means for supplying welding current 105 to the overlapped wire portions at each of the said points during only a portion of the time for which the same are pressed together.

46. In an appliance for electrically uniting end portions of a wire loop, electrodes disposed for clampingly engaging the overlapped wire portions respectively at a plurality of relative spaced points, a cam shaft arranged for successively forcing the respective electrodes into operative position, 115 and commutating means operated by said shaft for supplying current to each of the respective electrodes during only a portion of the time in which it is in operative position.

47. In an appliance for electrically uniting overlapping end portions of a wire loop, cam actuated means for successively gripping a portion of said loop, for severing the loop from the supply of wire, and for con- 120 125 130

- secutively pressing the overlapped wire portions against each other at a plurality of relatively spaced points; in combination with a commutator controlling a supply of welding current for each of the said relatively spaced points, and a single shaft jointly rotating the said commutator and the cams forming part of the said cam-actuated means.
10. 48. In an appliance for uniting an object encircling wire loop, means consecutively operating for gripping a portion of the loop, tensioning the loop, gripping another portion of the loop, and pressing terminal loop portions against each other; in combination with means for supplying a welding current to the said terminal loop portions for a part only of the time during which they are pressed against each other.
15. 49. In an appliance for banding an object with wire, means operable for the formation of a loop with a terminal end of the wire in lapping relation to a part of the loop, a plurality of holding devices acting successively for first gripping the terminal end of the wire and for thereafter gripping the lapping portions of said wire at a stage subsequently to placing the wire of the loop under tension, wire-tensioning means operable for retracting the wire of the loop prior to the gripping engagement of that holding device which engages the lapping portions of the wire, and a plurality of welding members acting successively for welding the lapping portions of the wire.
20. 50. In an appliance for banding an object with wire, means operable for the formation of a loop with a terminal end of the wire in lapping relation to a part of the loop, a plurality of holding devices acting successively for first gripping the terminal end of the wire and for thereafter gripping the lapping portions of said wire at a stage subsequently to placing the wire of the loop under tension, wire-tensioning means operable for retracting the wire of the loop prior to the gripping engagement of that holding device which engages the lapping portions of the wire, and electrical means for spot welding the lapping portions of said wire within the area intermediate the separated points of gripping engagement with the wire of the said plurality of holding devices.
25. 51. In an appliance for banding an object with wire, wire-feeding means operable for the formation of a loop with a terminal portion of the wire in lapping relation to the loop, holding means for said wire, a welding electrode movable to a position intermediate the wire and the surface of a package, a plurality of welding electrodes co-operable with the first named electrode, and service relation to the first named welding electrode.
30. 52. In an appliance for banding an object with wire, wire-feeding means operable for the formation of a loop with a terminal portion of the wire in lapping relation to the loop, holding means for said wire, a welding electrode movable to a position intermediate the wire and the surface of a package, a plurality of welding electrodes co-operable with the first named electrode, and means for effecting the successive movement of said plurality of electrodes into service relation to the first named electrode.
35. 53. In an appliance for banding an object with wire, wire-feeding means operable for the formation of a loop with a terminal portion of the wire in lapping relation to the loop, holding means for said wire, a welding electrode movable to a position intermediate the wire and the surface of a package, means for withdrawing said electrode from the service position between the wire and the package, a second welding electrode co-operable with the first welding electrode, and automatic means actuated to position the second welding electrode into service relation to the first welding electrode subsequently to the movement of the latter between the wire and the package.
40. 54. In an appliance for banding an object with wire, wire-feeding and tensioning means controllable for the formation of a loop and for thereafter tightening said loop around an object, means for retaining a terminal part of the loop in fixed lapping relation to another part of the loop prior to the tensioning action on the loop, separate means for fixedly retaining the two lapping portions of the loop subsequently to the tensioning action on the loop, means for severing the wire of the loop subsequently to the tensioning action, and means actuated subsequently to the second retaining means and to the severing means for joining the lapping portions of the loop in the area between the gripping contacts with the wire of the two said retaining means.
45. 55. In an appliance for banding an object with wire, wire-feeding and tensioning means controllable for the formation of a loop and for thereafter tightening said loop around an object, means operable at will for gripping a terminal part of said wire, separate means for gripping the overlapping parts of said wire at a point separated from the first gripping means, welding mechanism, and automatic means for actuating the second gripping means and the welding mechanism in successive order.
50. 56. In an appliance for banding an object with wire, wire-feeding and tensioning mechanism operable for the formation of a loop and for subsequently tensioning said

- loop, means operable at will for gripping a terminal part of said loop, a power-operated gripper for engagement with lapping portions of said loop, cutting means, welding means, and power-operated means for actuating the cutting means and the welding means in successive order.
57. In an appliance for banding an object with wire, wire-feeding and tensioning mechanism operable for the formation of a loop and for subsequently tensioning said loop, means operable at will for gripping a terminal part of said loop, a second gripping means engageable with lapping portions of said loop, welding means positioned for joining the lapping portions of the loop in the area intermediate the engagement with the loop of the first gripping means and the second gripping means, cutting means for severing the wire adjacent the first named gripping means, and shaft actuated means for successively operating the second named gripping means, the cutting means, and the welding means.
58. In an appliance for banding an object with wire, wire-feeding and tensioning mechanism operable for the formation of a loop and for subsequently tensioning said loop, a plurality of slidable members having means for moving the same into and out of operative positions intermediate the surface of a package and the wire of the loop, gripping means co-operable with certain of said slidable members and welding means co-operable with another of said slidable members, and means for actuating said gripping means and said welding means in due order.
59. In an appliance for banding an object with wire, wire-feeding and tensioning means operable for the formation of a wire loop and for tensioning said loop subsequently to such formation, a plurality of wire gripping devices separated from each other by an appreciable interval, one of which devices is operable for holding a terminal part of the wire and the other of which devices is operable by engagement with lapping portions of the wire, means for joining the lapping portions of the wire in the area intermediate the engagement with the wire of the two said gripping means, and means for severing the wire prior to the joining operation.
60. In an appliance for banding an ob-
- ject with wire, co-operable wire feeding rolls, co-operable wire-tensioning rolls, gripping means engageable with the wire subsequent to the formation of a loop by said wire-feeding rolls and prior to the action 60 of the tensioning rolls, and means for shifting the wire tensioning rolls and the wire feeding rolls alternately into service relation to the wire.
61. In an appliance for banding an object with wire, co-operable wire-feeding rolls, co-operable wire-tensioning rolls, gripping means engageable with the wire subsequently to the formation of a loop by said wire-feeding rolls and prior to the action 65 of the tensioning rolls, shifting means for moving the wire-feeding rolls into and out of service relation to the wire, other shifting means for controlling the wire-tensioning rolls to effect the engagement with and disengagement from the wire, and means for controlling the two said roll shifting means with the lapse of an appreciable interval of time between the service action of the wire-tensioning rolls and the movement to an out of service position of the wire-feeding rolls.
62. In an appliance for banding an object with wire, wire-feeding means operable for the formation of a wire loop, a carrier 85 movable relatively to said wire-feeding means, wire-tensioning means supported by said carrier and movable therewith relatively to the wire feeding means, means controlling the slideable travel of the carrier and the wire-tensioning means to pull the wire of the loop to a determined tension, gripping means, and wire joining means for uniting the wire of the loop when under 90 the desired tension.
63. In an appliance for banding an object with wire, wire-feeding means operable for the formation of a wire loop, a carrier movable relatively to said wire-feeding means, wire-tensioning means supported by said carrier and movable therewith relatively to the wire-feeding means, means yieldably opposing the travel of said carrier and the wire-tensioning means with respect to 100 the wire-feeding means, controlling means for the travel of said carrier under a desired tension of the loop, and wire joining means.

Signed at Chicago, August 2nd, 1918.
JOHN SHERMAN McCHESNEY.
